United States Patent Office.

ZENO KELLEY, OF NEW BEDFORD, MASSACHUSETTS.

Letters Patent No. 78,673, dated June 9, 1868.

IMPROVEMENT IN BOMB-LANCES FOR KILLING WHALES.

The Schedule referred to in these Letters Patent and making part of the same.

TO ALL WHOM IT MAY CONCERN:

Be it known that I, ZENO KELLEY, of New Bedford, in the county of Bristol, and State of Massachusetts, have invented certain new and useful Improvements in Harpoons; and I do hereby declare that the following is a full, clear, and exact description thereof, reference being had to the accompanying drawings, and to the letters of reference marked thereon, which form a part of this specification, in which—

Figure 1 is a plan view of my harpoon.

Figure 2 is a longitudinal section of the same.

The letter A represents the shaft of my harpoon, and is formed of two sections, c and d, section c having a hole in its lower end, in which the upper end of section d is made to fit.

The section d is reduced in size from the point s to the end that connects it with section c. The object of this reduced portion of d is to receive the slide e, which is allowed to play between the point s and the adjustable shoulder t. Between the shoulder t and slide e a spiral spring is placed, the object of which will be hereafter seen.

E represents the harpoon-head, which fits in a socket at the lower end of section d.

In the neck of the harpoon-head which enters d, as above described, a percussion-cap, o, is inserted, the head itself being filled with gunpowder.

In order to explode the powder by the agency of said cap, the following devices are used: First, the cross-bar g, which is pivoted in slot n. The said bar may be so constructed as that its lower end will be flush with the side of the harpoon, so that it will give no resistance when entering the whale, the upper end of said bar g being made to project sufficiently far above the section d as that a cord attached to said section will draw the said bar at right angles to the harpoon, and, by its resistance, prevent the whale from escaping. The bar g has on its upper edge the pin i, the office of which will be hereafter seen.

V represents the hammer which explodes the cap. The said hammer is provided with a cylindrical rod, j, which extends in the direction of bar g, as seen in fig. 2. Near the end of said rod the pin a is inserted, the said pin serving the purpose of keeping in place the metal plate m.

The plate m, it will be observed, has a hole near its inner end, which is intended for the admission of pin i when the harpoon is prepared for striking a whale.

h represents a spiral spring, which is placed directly behind the hammer V, and designed by its action to give the hammer sufficient momentum to explode the cap.

When preparing to strike a whale, the following operations are to be observed: The harpoon-head being charged with powder, the plate m must be pushed back until the pin i will enter the hole in said plate. In pushing back plate m, the cylindrical rod j, with hammer V attached to it, will be drawn back by the action of pin n. The drawing back the hammer V will compress the spiral spring h, and keep it in position to act on the hammer when required. Cords now being inserted through the holes in slide e, the harpoon may be thrown by hand, or, if desired, section c can be inserted in a gun, and the harpoon shot into the whale. When the point of the harpoon has penetrated the fish as far as the lower end of bar g, the said end will be forced out, the pin i released from the hole in m, and spiral spring h, being left free to act, will drive the hammer V with sufficient force against the cap o to explode the powder in the harpoon-head E.

The sections c and d will be uninjured, and can be used again.

Figure 3 represents the iron breech-piece L, with an elliptical spring, f, attached to it, which can be placed against the shoulder to break the force of the recoil when a gun is used to discharge the shaft.

It will be remarked that a ball may be inserted in the head E with the charge of powder; and further, that a gum-elastic or spiral spring may be used for the breech-piece.

Having thus described my invention, what I claim, and desire to secure by Letters Patent, is—

The hammer V, spring h, rod j, pin i, and bar g, in combination with head E, all arranged as and for the purpose set forth.

In testimony that I claim the foregoing as my own, I affix my signature in presence of two witnesses.

ZENO KELLEY.
